Patented May 25, 1915.

UNITED STATES PATENT OFFICE.

JOHN H. RICHARDSON, OF MELROSE, MASSACHUSETTS, ASSIGNOR TO UNITED SHOE MACHINERY COMPANY, OF PATERSON, NEW JERSEY, A CORPORATION OF NEW JERSEY.

RESURFACING-TOOL.

1,140,398.

Specification of Letters Patent. Patented May 25, 1915.

Application filed August 4, 1913. Serial No. 782,855.

To all whom it may concern:

Be it known that I, JOHN H. RICHARDSON, a citizen of the United States, residing at Melrose, in the county of Middlesex and 5 State of Massachusetts, have invented certain Improvements in Resurfacing-Tools, of which the following description, in connection with the accompanying drawings, is a specification, like reference characters on the 10 drawings indicating like parts in the several figures.

This invention relates to resurfacing tools, and particularly to that class of tools the function of which is to finish different parts 15 of the surface in succession by removing at each operation a portion of material of definite width and of a depth sufficient to provide the character of surface desired. Such tools are usually in the form of planes, and 20 the preferred embodiment of the invention herein described and shown comprises a plane having the above mentioned general characteristics, although it should be understood that the invention is not limited to a 25 tool constructed to form plane surfaces.

An immediate object of the invention is to provide a tool which shall be especially useful for re-finishing the surfaces of cutting blocks such as are used in die presses, 30 and more particularly the blocks used in a type of machine known as the clicking machine which is employed extensively for dieing out uppers and linings in the manufacture 35 of boots and shoes. Portions of these blocks are subject to considerable wear in the cutting operation, and since it is necessary for the best results that the block shall oppose a substantially plane, smooth surface 40 to the cutting edge of the die, frequent resurfacing is necessary. These blocks are commonly made of hard and resistant material, and when constructed of wood are so arranged that the working surface is across 45 the grain of the wood. It follows that in resurfacing such a block by the use of a hand tool it is possible to operate effectively at one time upon only a small portion of the surface. For this reason tools of the general 50 class to which this invention relates are especially adapted for this purpose.

In view of the variation in character of the material of which different blocks are composed, as well as the differences in ability among different operatives, it is obvious 55 that a resurfacing tool constructed to oper-

ate invariably upon the same extent of surface will not be adapted for the best results under all conditions of use.

An object of this invention, therefore, among others, is to provide a tool of the 60 character referred to which shall be better adapted than prior constructions to meet varying requirements.

To this end a feature of the invention consists in the provision of means whereby the 65 tool may be rendered variably effective upon portions of the material varying in extent to suit the convenience of the operator, without detracting from the efficiency of the tool as a means for forming under all conditions 70 a substantially smooth surface of regular contour. The preferred construction comprises a plane in which the cutter projects laterally beyond a side portion thereof arranged to act as a guide with reference to 75 the edge of the unfinished portion of the surface of the block or similar object to be finished, and which includes provision for adjusting suitably the lateral projection of the cutter.

A further feature resides in the provision of means for insuring a proper degree of bevel at the cutting edges of the blade, and also preferably a proper angular relation of the cutting edges to the direction of the 85 length of the blade, and includes a member which is shaped to engage the cutter in fixed angular relation thereto and constitutes conveniently a portion of a clamping device for securing the cutter in position, this member 90 being formed to serve as a gage for indicating the proper degree of bevel at the cutting edges, as well as the proper inclination of these edges with respect to the length of the blade, when the blade is ground.

Other features of the invention, including certain details of construction and combinations of parts, will not be described with reference to the accompanying drawings and pointed out in the appended claims.

In the drawings, Figure 1 is a perspective view of a preferred form of tool embodying the present invention, Fig. 2 is a similar view of the front portion of the tool as seen from the opposite side with reference to Fig. 1, Fig. 105 3 is a perspective view of the middle portion of the tool, looking upwardly from a position at one side thereof, and with the guide at the side of the tool removed, Fig. 4 is a 110 transverse section showing the cutter and a

- portion of the adjusting means, Fig. 5 shows the cutter and parts of the holder in disassembled relation, and Fig. 6 is a perspective view of an end portion of the blade and the clamping member in their normal operative relation, illustrating features of construction of the clamping member whereby the latter may be used as a gage when the blade is ground.
- 10 The tool illustrated is designed for finishing plane surfaces, and includes a stock having a body portion or member 2 formed with a plane lower face and elongated in the direction of operative movement of the tool and handles 4 and 6 whereby the tool may be operated. Formed preferably integral with the portion 2 is an upwardly projecting side portion or flange 8 of the stock to which is secured by means of clamping screws 10 a guide member 12 also formed with a plane lower face which is normally parallel to and spaced somewhat above the lower face of the portion 2 for a purpose which will be subsequently explained. The 15 vertical side portion of the member 12 is formed with slots, one of which is shown at 14 in Fig. 2, through which the screws 10 pass, so that the guide 12 may be adjusted vertically with respect to the member 2 to 20 vary the distance of its lower face above the lower face of said member.
- 25 Mounted upon the member 2 is a holder 16 which is suitably shaped to support a cutter 18 and carries a clamping screw 20 for 30 securing the cutter adjustably thereon. The cutter consists of two blade portions preferably formed integral, and shaped at their ends to provide cutting edges 22 and 24 in planes substantially at right angles to each 35 other. The cutting edges are backed off at an angle to the direction of the length of the cutter so that when the cutter is in position on the holder the edge 22 will be substantially vertical and the edge 24 approximately at right angles to the direction of the length of the tool. One end of the holder 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940
- 5 The screw 32 is threaded through a bridge

piece 34 formed integral with the members 2 and 8, and engages a bearing block 36 which is shaped to fit upon the upper side of the cutter. The end of the screw enters a slot 38 formed transversely of the block so as to prevent longitudinal movement of the block with respect to the cutter. The screw 32 thus assists in retaining the cutter in position upon the holder, and also serves as a means to swing the holder about its axis in a direction opposite to that of the movement imparted thereto by the screw 30. The members 2 and 8 are broken away, as shown at 40, and the guide member 12 is outwardly curved as shown at 42, to provide for the projection of the cutter and the lateral adjustment of the cutter and holder. The holder has a downwardly projecting foot 44 which is positioned within the recess provided in the member 2, with its lower face approximately in the plane of the lower face of this member.

In the use of the tool the member 12 is adjusted so that the distance between its lower face and the lower face of the member 2 may equal the depth of material which it is desired to remove from the surface of the object to be finished, and the holder 16 is adjusted about its pivot so that the cutter may project laterally beyond the edge 46 of the member 2 a distance equal to the desired width of the portion of material which is to be removed at each operative movement of the tool. With the parts adjusted in this manner that portion of the edge 46 of the member 2 forwardly of the cutter is placed in contact with the edge of the object to be finished, such as a cutting block of the type above referred to, and the tool is supported with the lower face of the guide member 12 resting upon the surface to be finished. The edge 46 of the member 2 thus serves as means for positioning the tool laterally with reference to the edge of the surface to be finished. Forward movement of the tool now causes the cutter to remove from this surface, at one edge, a portion of material of a depth and width previously determined by the above described adjustments respectively of the guide 12 and the holder 16. This provides a narrow finished surface upon which the lower face of the member 2 rests on a succeeding similar movement of the tool, while the guide 12 again rests upon the unfinished portion. The surface material is thus removed in successive increments, as the tool advances laterally over the work on its successive operative movements, until the entire surface has been re-finished.

For most purposes the cutter will preferably be projected but slightly beyond the edge 46, so as to remove a comparatively narrow portion of the material, and the width of the cut may be regulated readily

as desired by the previously described adjustment of the holder 16, while the depth of cut is regulated by adjustment of the member 12. The holder is preferably pivoted upon its supporting member, as shown, at a point remote from the projecting edge portion of the cutter, so that lateral adjustment of the cutter may be effected as required without altering materially the angular relation of the cutter to the lateral edge 46.

The elongation of the members 2 and 12 insures that the operative movement of the tool shall be substantially in a straight line. In order to keep the tool to a true plane of operation with reference to its lateral advance, the cutter is preferably so ground and the holder so arranged that the cutting edge 24 may incline slightly downward toward the point formed by the junction of the edges 22 and 24, and the blade is adjusted lengthwise of the holder so that this point may project slightly below the plane of the lower surface of the member 2. This has the effect of insuring that the blade shall remove at each operation material of a depth fully equal to the distance between the lower faces of the members 2 and 12 and keeps these members in full contact respectively with the finished and the unfinished portions of the surface.

The block 36, as shown clearly in Figs. 5 and 6, is so shaped as to fit the cutter blade accurately and maintain the same angular relation to the blade whatever its longitudinal position may be with respect to the blade. Upon the end of the block adjacent to the cutting edges of the blade, moreover, are formed edges or faces 48 and 50 which are parallel respectively to the cutting edges 22 and 24 when the blade is correctly ground. The block 36 thus serves conveniently as a gage which may be used in the grinding of the cutter to indicate the correct angular relation of the cutting edges to the length of the blade. The block 36 has also another function, which is clearly apparent by reference to Figs. 5 and 6. It will be understood that since either side portion of the blade is inclined comparatively little to the direction of movement of the tool, it is necessary that the blade be ground on a rather long bevel at the cutting edges if the tool is to do its work effectively. It is also important, for the sake of the strength of the blade, that the bevel should not be longer than necessary. The block 36 therefore is shaped so as to indicate the proper degree of the bevel of the cutting edges as well as the angular relation of the edges to the direction of the length of the blade. To this end the block is formed with side portions 52 that overlap and fit upon the lateral edges of the blade and are formed each with an inclined edge or face

54 that is parallel to the beveled face 56 of the blade when the latter is properly ground and therefore serves to indicate the proper degree of bevel of the blade. The overlapping portions 52 assist likewise in preventing lateral displacement of the block with respect to the blade and in keeping the two in fixed angular relation to each other.

It will be understood that when the blade is detached for grinding the block 36 also is detached so that it may be applied to the blade to indicate the proper angle for the cutting edges and the proper degree of bevel. For the former purpose the block is applied to the blade with its edges 48 and 50 directly adjacent to the edges 22 and 24, and for indicating the bevel the block is moved along the blade until, if the grinding is done properly, the edges or faces 54 lie substantially in the respective planes of the bevel.

Although the above description has reference to the specific details of construction of the preferred embodiment of the invention illustrated in the drawings, it will be understood that variations from these precise details are comprehended within the spirit and scope of the claims.

Having described the invention, what I claim as new and desire to secure by Letters Patent of the United States is the following:

1. A resurfacing tool having, in combination, guiding means for positioning the tool laterally with reference to the edge of the surface to be finished, and a cutter suitably projected to operate upon said surface, said cutter having provision for lateral adjustment with reference to said guiding means to vary the lateral range of operation thereof without varying the depth of the cut.

2. A resurfacing tool having, in combination, guiding means for positioning the tool laterally with reference to the edge of the surface to be finished, a cutter arranged with reference to said guiding means to remove a portion of the material at the edge of said surface on an operative movement of the tool, and means for varying the relative positions of said cutter and guiding means to vary the width of the portion so removed without varying the depth of the cut.

3. A resurfacing tool having, in combination, guiding means for positioning the tool laterally with reference to the edge of the surface to be finished, said means comprising a member having a lateral edge arranged to contact with the object to be finished at the edge of the unfinished surface, and a cutter projecting laterally beyond the edge of said member so as to remove a portion of the material at the edge of said surface on a forward movement of the tool, said cutter having provision for adjustment to vary the extent of its projection beyond said lateral

- edge without varying the extent of downward projection of the cutter.
4. A tool of the class described having, in combination, a cutter, guiding means arranged with reference to the cutter to cause the latter to remove a portion of predetermined depth and width from one edge of the surface to be finished on an operative movement of the tool, and means for varying the relative positions of said cutter and guiding means to cause the cutter to remove from said surface portions of varying widths and equal depths.
5. A tool for forming a finished surface upon an object by removing successive increments of material of predetermined lateral extent having, in combination, a cutter, means for guiding the tool in its movement with reference to both the top and lateral surfaces of the unfinished portion of the object, and means for adjusting the cutter laterally with reference to said guiding means to vary the lateral extent of the portion removed on an operative movement of the tool without varying the depth of the cut.
6. A tool for refinishing a plane surface having, in combination, a body portion with a plane face arranged to rest upon the finished portion of the surface, a side portion having a face in a higher plane arranged to rest upon the unfinished portion of the surface, and a cutter having a cutting edge projecting laterally beyond the face of said body portion and beneath the face of said side portion and formed to remove the material at the edge of the unfinished portion of the surface on a forward movement of the tool, said cutter being adjustable to vary the extent of the projection thereof beyond the side of said body portion without altering the extent of its downward projection.
7. A tool of the class described comprising, in combination, a body member having a lateral edge for positioning the tool with reference to the edge of the surface to be finished, a cutter carried by said member and suitably projected beyond said lateral edge to remove a portion of material of predetermined width from the edge of said surface on an operative movement of the tool, and a holder mounted on said member and arranged to support said cutter, said holder having provision for swinging movement upon said member so as to vary the extent of said lateral projection of the cutter.
8. A tool of the class described comprising, in combination, a body member having a lateral edge for positioning the tool with reference to the edge of the surface to be finished, a cutter carried by said member and arranged with its cutting edge projecting beyond the lateral edge of said member, and a holder for the cutter pivotally mounted upon said member at a point remote from said edge portion of the cutter so as to permit variation of the extent of said projection of the cutter without altering materially the angular relation of the cutter to the lateral edge of said body member.
9. A tool of the class described comprising, in combination, a body member having a lateral edge for positioning the tool with reference to the edge of the surface to be finished, a cutter carried by said member and arranged with one end thereof projecting beyond said lateral edge, a holder for the cutter pivotally mounted upon said member, and means arranged to operate upon said holder from opposite sides to swing said holder in either direction about its axis and thereby vary the extent of said projection of the cutter.
10. In a plane of the class described, the combination with the plane stock of a cutter mounted on the stock and comprising a blade beveled at one end to form a cutting edge, and means for securing said blade in position on the stock at an angle to the direction of movement of the plane including a member shaped to engage the blade in fixed angular relation thereto, said member having means for indicating the proper degree of bevel at the cutting edge of the blade, whereby said member may be used as a gage when the blade is ground.
11. In a plane of the class described, the combination with the plane stock, of a cutter mounted on the stock and comprising a blade one of the faces of which is beveled at one end to form a cutting edge, and means for securing the blade in operative position on the stock at an angle to the direction of movement of the plane comprising a member shaped to engage the opposite face of the blade and maintain a fixed angular relation to the length of the blade without preventing relative longitudinal movement of said member and blade, said member having means for indicating the proper degree of bevel at the cutting edge of the blade.
12. In a plane of the class described, the combination with the plane stock, of a cutter mounted on the stock and comprising a blade beveled at one end to form a cutting edge, and means for securing the blade in operative position on the stock at an angle to the direction of movement of the plane comprising a member shaped to engage the blade in fixed angular relation thereto and having a portion formed to project over the lateral edge of the blade, said projecting portion being shaped to present an edge substantially parallel to the plane of the bevel at the cutting edge of the blade, whereby said member may be used as a gage to indicate the proper degree of bevel when the blade is ground.
13. In a plane of the class described, the combination with the plane stock, of a cutter mounted on the stock and comprising

a blade having its side portions arranged to form an angle with each other and its outer faces beveled at one end to form cutting edges, and means for securing the blade in operative position on the stock at an angle to the direction of movement of the plane comprising a member shaped to rest within the angle of said blade in fixed angular relation thereto and having side portions 5 formed to overlap the lateral edges of said blade, said overlapping portions being shaped to present faces substantially parallel respectively to the planes of the bevel at said cutting edges, whereby said member 10 may be used as a gage to indicate the proper degree of bevel when the blade is ground.

14. In a plane of the class described, the combination with the plane stock, of a cutter mounted on the stock and comprising a 15 blade having cutting edges arranged at an angle to each other, and means for securing the blade in operative position on the stock at an angle to the direction of movement of the plane comprising a bearing block shaped 20 to engage the blade in fixed angular relation thereto and constituting a portion of a clamping device for securing the blade in position, said block being shaped at one end to present edges substantially parallel respectively to 25 the cutting edges of the blade, whereby the block may be used as a gage to indicate the correct angular relation of said cutting edges to the length of the blade when the blade is ground.

30 15. In a plane of the class described, the combination with the plane stock, of a cutter mounted on the stock and comprising a blade having its side portions arranged to form an angle with each other and having 35 cutting edges at one end of said blade, and means for securing the blade in operative 40 position on the stock at an angle to the direction of movement of the plane comprising a member shaped to rest within the angle of said blade in fixed angular relation thereto, said member being shaped at one 45 end to present edges substantially parallel respectively to the cutting edges of the blade, whereby the block may be used as a 50 gage to indicate the correct angular relation

of said cutting edges to the length of the blade.

16. In a plane of the class described, the combination with the plane stock, of a cutter mounted on the stock and comprising a 55 blade having its side portions arranged to form an angle with each other and its outer faces beveled at one end to form cutting edges, and means for securing the blade in operative position on the stock at an angle 60 to the direction of movement of the plane comprising a member shaped to rest within the angle of said blade in fixed angular relation thereto, said member having means for indicating the proper degree of bevel at the 65 cutting edges of the blade and being shaped also to present edges substantially parallel respectively to the cutting edges of the blade so as to indicate the correct angular relation of said cutting edges to the length of 70 the blade.

17. A plane comprising, in combination, a plane stock having a lateral guiding edge, a cutter carried by the stock and arranged with its cutting edge projecting beyond said 75 lateral edge of the stock, and a holder for the cutter adjustable with reference to the stock to cause the cutter to be projected different distances laterally beyond the guiding edge of the stock. 80

18. A plane comprising, in combination, a plane stock having a lateral guiding edge and a lower face arranged to rest upon the finished portion of the material, a cutter carried by the stock and arranged with its 85 cutting edge projecting beyond said lateral edge of the stock, and a holder for the cutter adjustable with reference to the stock in a plane substantially parallel to the lower face of the stock to cause the cutter to be 90 projected different distances laterally beyond the guiding edge of the stock.

In testimony whereof I have signed my name to this specification in the presence of two subscribing witnesses.

JOHN H. RICHARDSON.
